& Bear, LLP

(57) **CLAIM**

The ornamental design for a bike, as shown and described.

DESCRIPTION

FIG. 1 is a rear, top, and left side perspective view of a bike of our design;
FIG. 2 is a rear, top, and right side perspective view thereof;
FIG. 3 is a front, top, and left side perspective view thereof;
FIG. 4 is a front, top, and right side perspective view thereof;
FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines are included for the purpose of illustrating portions of the bike and form no part of the claimed design.

1 Claim, 10 Drawing Sheets
